UNITED STATES PATENT OFFICE.

HIRAM G. SEDGWICK, OF MILL VALLEY, CALIFORNIA.

AUTOMATIC ELECTRICAL TRAIN-STOP.

No. 852,628.

Specification of Letters Patent.

Patented May 7, 1907.

Application filed November 24, 1905. Serial No. 288,916.

To all whom it may concern:

Be it known that I, HIRAM G. SEDGWICK, a citizen of the United States of America, and a resident of Mill Valley, county of Marin, State of California, have invented certain new and useful Improvements in Automatic Electrical Train-Stops, of which the following is a full and clear specification, reference being had to the accompanying drawings, in which,—

Figure 1 is a diagram of a portion of a roadbed showing the present improvements applied thereto; Fig. 2 a similar view showing a cross-over with the invention applied to the same; Fig. 3 a diagrammatic view of the supplemental switch-box employed in the present invention; and Fig. 4 a view showing the supplemental or intermediate system of contacts arranged for a crossing.

This invention has particular reference to the automatic block system for train-stopping apparatus covered by my co-pending application numbered 288,914 in which the locomotive is provided with an electrically-controlled valve which when actuated vents the train-pipe of the brake mechanism and sets the brakes, the actuation of the valve being accomplished by a pair of insulated stopping contacts suitably mounted on the roadbed adjacent to the rails and adapted to simultaneously make contact with a pair of brushes or other contacts on the locomotive, so that when said roadbed-contacts are made the terminals of a battery a current will be sent through a circuit on the locomotive and thereby actuate the vent-valve. In connection with the stopping-contacts I also employ a pair of setting-contacts which are adapted to co-act with another pair of brushes or contacts on the locomotive in such manner as to send a current through certain switches and thereby automatically set or render active the stopping-contacts, which latter are arranged at a proper distance behind the train in double track roads and both behind and in front of the train in single-track roads, so that as the train proceeds on its journey it will automatically preempt to itself sections of the track. In addition to these stopping and setting-contacts I employ another pair of contacts which serve to restore the switches to normal and thereby render inactive the stopping-contacts.

In my present improvements I employ the

same system of contacts on the roadbed but 55 in addition I provide a supplemental system of contacts for use at side-tracks, junctions, crossovers, and crossings, whereby a passing train will be protected against trains entering or crossing the main track and whereby a 60 train entering the main track from a junction or side-track or cross-over will automatically protect itself in the same manner as when running on the main track, as more fully hereinafter set forth. 65

Referring to Fig. 1, which shows these improvements applied to a side-track and a junction, d' represents the main switch boxes at the respective ends of the block, these boxes containing the switches and circuits as 70 shown in my former application hereinbefore referred to. In connection with each of these switch-boxes is employed a pair of stopping-contacts a' connected to the box by wires g' , a pair of setting-contacts b' connected to the box by wires l' , and a pair of restore-contacts c' connected to the box by the wires b^2 , these contacts and conductors being arranged as in my former application. When a train passes over the setting contacts b' , the 80 switches and circuits set forth in my former application render the stopping-contacts a' at both ends of the block active so that no train can enter the block, and when the train reaches the end of the block going in either 85 direction it passes over the restore-contacts c' and restores the parts to normal and thereby renders both pairs of contacts a' inactive. The two main switch-boxes are connected by the line wires e' and f' . 90

At a point intermediate the two main switch-boxes d' and adjacent to the side-track and junction I provide a supplemental switch-box d'' and run the line wires e' and f'' therethrough and connect them up to 95 switches and circuits in such manner that the supplemental series of contacts are at times thrown into circuit with the main contacts of the block.

Along each side of the side-track I locate a 100 supplemental series of contacts consisting of the safety-contacts a'' , the setting-contacts b'' , and restore-contacts c'' . On the junction line I also locate a series of supplemental contacts consisting of the stopping-contacts 105 a''' , the setting-contacts b''' and the restore contacts c''' . All the supplemental stopping-contacts a'' and a''' are connected in

multiple to the supplemental switch-box d'' by wires g'' , the setting-contacts b'' and b''' by wires l'' , and the restore-contacts c'' and c''' by wires b^2 . These supplemental contacts are connected up to the main contacts in such manner that a train passing over either pair of these main setting-contacts b' will not only set the main stopping-contacts but will also render active or set all the supplemental safety-contacts and when the train reaches the end of the block will restore said stopping-contacts to normal inactive condition, whereby trains will be prevented from entering the protected block from either the side-track or the junction track until the train that has preempted the block has passed therefrom. Should a train enter the main track from the junction track, supplemental contacts b''' will cause not only the supplemental stopping-contacts to be made active but also the main stopping-contacts a' , so that said train will be protected against trains moving in either direction on the main track and against a train that might attempt to leave the side-track. It will be observed also that should a train pass from the main track on to the junction track it will pass over supplemental contacts c''' and thereby restore all the stopping-contacts behind it and leave the main track and the side-track free. Should a train pass on to the side-track it will first pass over the restore-contacts c'' and thereby free the main track, but should it attempt to leave the side-track and go back on to the main track it will have to pass over a pair of supplemental setting-contacts b'' and in that way set the main stopping-contacts a' .

The manner of connecting up the supplemental wires l'' , g'' and b^2 to the main line wires e' and f' is shown in Fig. 3. At the left of the supplemental switch-box d'' the line setting-wire f' passes in through a relay switch r' , thence through a contact-screw g^2 , thence through the lever r^2 of switch n' and thence out of the box again at the binding-post r^3 , and thence to the other main switch-box d' . The line restore-wire e' enters the supplemental switch-box at the right-hand side, thence passes through a relay switch v' , thence through a contact-screw x^2 , thence through the armature-arm of a sounder-switch y' , and thence out through binding-post x^3 and on to the next main switch-box d' .

The line wire f' is part of the setting mechanism and the wire e' is part of the restoring mechanism. When current is sent through wire f' it actuates relay switch r' and thereby closes a circuit t' included in which is a battery m' , the magnet j' of a double switch h' . When this circuit t' is thus closed the switch h' is closed and battery i' is thrown into circuit with the pair of

wires g'' leading to all of the supplemental stopping-contacts, thereby making said contacts the terminals of the battery i' and putting them in active condition. From the relay switch r' the current passes out through binding-post r^3 and thence on to the next main switch-box where it sets the main stopping-contacts and passes to ground.

A current passing into the supplemental switch-box through restore wire e' first closes relay switch v' and thence passes out through binding-post x^3 and thence on to the other switch box where it restores the main safety-contacts and passes to ground. The closing of relay switch v' opens switch h' through the medium of battery w' , circuit u' and magnet k' and thus disconnects battery i' from the supplemental stopping-contacts.

Should circuit l' be closed through the medium of the supplemental setting-contacts, the magnet of switch n' will be energized and thus close the circuit of battery o' and actuate switch r' , thus energizing magnet j' and closing the switch h' , thereby setting the supplemental stopping-contacts. The current from battery o' , through the connections shown at the left-hand side of Fig. 3, passes in both directions through setting wires f' through both the main switch-boxes d' and sets both pairs of main safety-contacts and thence goes to ground. When any one of the pairs of supplemental restore-contacts are bridged by the brushes on the locomotive, the magnet of switch y' is energized, through the medium of battery w' and wires b^2 , thus actuating the armature x' of said switch y' . The actuation of this arm x' closes the circuit z' of battery c^2 , included in which is contact-screw z^2 , a contact-screw carried by an insulated part x^3 mounted on said arm x' in such manner that when said arm is drawn down said contact screw will make contact with the bracket supporting contact-screw x^2 . In this way the current from battery c^2 is sent through switch v' and thence on to similar switches in the main switch-boxes and thence to ground, thus opening switch h' and both the similar switches in the main switch-boxes thus restoring all the parts to normal.

It will be obvious that this compound or supplemental system of contacts may be used in a great variety of ways. In Fig. 2 I have shown it adapted for use at a cross-over in which it is obvious that a train using this cross-over will protect itself from trains on either of the main tracks and that trains on the main track will automatically close the cross-over track while they are within the block in which the cross-over track is located.

In Fig. 4 I have shown this system arranged for use at a crossing, so that a train passing over any pair of setting-contacts will

set all the stopping contacts, thus protecting itself on all sides.

It will be observed that where I use the term "intersecting track" in the claims I employ it in its generic sense, to include not only crossing tracks but also the tracks of cross-overs, sidings, etc., the special object of the present invention being to provide supplemental protecting means which are capable of use in connection with the main block system without disarranging the same, as hereinbefore set forth.

What I claim and desire to secure by Letters Patent is:—

1. In an apparatus of the class set forth, the combination with a main track and another track adjacent the main track, stopping-contacts and setting-contacts and restore-contacts on the main track at each side of the connecting track, a similar series of contacts on the adjacent track, and electrical connections whereby said main and supplemental series of contacts are rendered mutually co-operative, substantially as set forth.

2. In combination with a main track and another track adjacent thereto, of an electrical stopping system therefor consisting of a series of main stopping contacts independent of the rails on the main track at each side of the adjacent track, a series of stopping-contacts on the adjacent track, and electrical means connecting the three series of contacts, for the purposes set forth.

3. In combination with a main track and an adjacent track, a pair of stopping-contacts independent of the rails on the main track at each side of the adjacent track, a supplemental pair of stopping contacts on the adjacent track, and independent of the rails and electrical devices for simultaneously rendering these contacts active, and devices for simultaneously restoring them to normal.

4. In combination with a main track and a connecting track, stopping-contacts on the main track at either side of the connecting track and a pair of supplemental stopping-contacts on the connecting track, a pair of setting-contacts adjacent to each pair of safety-contacts, means whereby all the safety-contacts are rendered active through the medium of the setting-contacts when a train passes over the setting-contacts, and means adapted to be actuated by a passing train for restoring the stopping-contacts to normal.

5. In a train-stopping system for a crossing, the combination of a stopping device on each track at a distance from the intersection of the tracks, train-operated setting-means on each track nearer the intersection, means whereby a train passing toward the intersection over any setting-means will render all the stopping-contacts active and train-operated means operable by a train after passing the intersection whereby all the

stopping-contacts are rendered inactive, for the purpose set forth.

6. In a system of the character set forth, a stopping device on the roadbed, a setting device beyond the same and a restore device 70 beyond the setting device, and a reversed series of stopping and setting and restoring devices on the opposite side of the roadbed, and electrical connections between said two series of devices whereby the operation of 75 either setting device will render both stopping devices active, and a supplemental series of stopping, setting and restoring devices connected with the aforesaid series of devices at a point between the restore devices 80 of the two series of devices and arranged on an intersecting track, whereby the supplemental devices will be mutually co-operative with the main devices, for the purpose set forth. 85

7. In a system of the character set forth, the combination of a stopping device, a setting device and a restore device, arranged in the order set forth on the roadbed, a reversed series of stopping, setting and restore devices 90 on the opposite side of the roadbed, an intersecting track having on its roadbed a similar reversed series of stopping devices, setting devices and restore devices, and means whereby said several series of devices are 95 mutually co-operative, for the purpose set forth.

8. In a train-stopping system for a crossing the combination of stopping devices on each track at a distance from the intersection of the tracks, train-operated setting devices on each track, and electrical means whereby a train passing over any setting device will render all the stopping devices active, and train-operated means whereby all 100 the stopping-contacts will be rendered inactive after the train passes the intersection of the tracks. 105

9. In a system of the character set forth, the combination of a stopping device a setting device and a restore device, arranged in the order named, on the roadbed, electrical means for the purpose set forth, a stopping device on an intersecting track intermediate the aforesaid setting device and the restore 110 device, a setting device and a restore device on this latter track, and electrical means connecting these latter stopping, setting and restore devices with the electrical means connecting the aforesaid series of devices, for 115 the purpose set forth. 120

10. In an automatic block system of the character set forth, a series of stopping, setting, and restoring devices located on the main track and electrically connected and 125 embodying means whereby a train passing over them will set the stopping devices behind it and then at the end of the block restore the stopping devices to normal, a series of supplemental stopping, setting, and 130

restoring devices on an adjacent track, and
means whereby this supplemental series is
electrically connected with the main series
between the setting and restoring devices of
the main series, whereby the main series and
the supplemental series are rendered mu-
tually co-operative.

In testimony whereof I hereunto affix my
signature in the presence of two witnesses
this 4th day of November 1905.

HIRAM G. SEDGWICK.
